UNITED STATES PATENT OFFICE

JOSEPH C. EGIZIO, OF ALLENTEWON, PENNSYLVANIA

DESIGN FOR A BOTTLE

Application filed August 10, 1931. Serial No. 40,810. Term of patent 7 years.

To all whom it may concern:

Be it known that I, JOSEPH C. EGIZIO, a citizen of the United States, residing at 628 N. Front St., city of Allentown, in the county of Lehigh and State of Pennsylvania, have invented a new, original, and ornamental Design for Bottles, of which the following is a specification, reference being had to the accompanying drawing, forming part thereof.

The figure is a side view in elevation of a bottle, showing my new design. The bottle has the same appearance when viewed from any side.

I claim:

The ornamental design for a bottle, as shown and described.

JOSEPH C. EGIZIO.
